US00D900346S

(12) **United States Design Patent** (10) **Patent No.:** **US D900,346 S**
(45) **Date of Patent:** **** Oct. 27, 2020**

(54) **FLOORING MODULE**

(71) Applicant: **EverBlock Systems, LLC**, New York, NY (US)

(72) Inventor: **Arnon Rosan**, New York, NY (US)

(73) Assignee: **EverBlock Systems LLC**, New York, NY (US)

(**) Term: **15 Years**

(21) Appl. No.: **29/640,623**

(22) Filed: **Mar. 15, 2018**

(51) LOC (12) Cl. **25-01**

(52) U.S. Cl.

USPC **D25/138**

(58) **Field of Classification Search**

USPC D25/138, 139, 140, 142, 143, 144, 149,

(57) **CLAIM**

The ornamental design for a flooring module, as shown and described.

DESCRIPTION

FIG. 1 is a top isometric view of a first embodiment of a flooring module showing my new design.

FIG. 2 is a top plan view of the flooring module of FIG. 1.

FIG. 3 is a bottom isometric view of the flooring module of FIG. 1.

FIG. 4 is bottom plan view of the flooring module of FIG. 1.

FIG. 5 is a right side elevation view of the flooring module of FIG. 1.

FIG. 6 is left side elevation view of the flooring module of FIG. 1.

FIG. 7 is front elevation view of the flooring module of FIG. 1.

FIG. 8 is a back elevation view of the flooring module of FIG. 1.

FIG. 9 is a top isometric view of a second embodiment of a flooring module; and,

FIG. 10 is a bottom isometric view of the flooring module of FIG. 9.

The flooring module is shown with symbolic breaks in its length in Embodiment 2. The appearance of any portion of the article between break lines forms no part of the claimed design.

1 Claim, 7 Drawing Sheets

US D900,346 S
